INVENTOR

Hans J. Diem,
BY Charles R. Seale

ATTORNEY

UNITED STATES PATENT OFFICE.

HANS J. DIEM, OF NEW YORK, N. Y., ASSIGNOR OF ONE-HALF TO SANFORD NARROW FABRIC CO., OF NEW YORK, N. Y., A CORPORATION OF NEW YORK.

MITTEN.

1,280,421.

Specification of Letters Patent.

Patented Oct. 1, 1918.

Application filed December 6, 1917. Serial No. 205,811.

To all whom it may concern:

Be it known that I, HANS J. DIEM, a citizen of Switzerland, residing in the city of New York, borough of Manhattan, in the 5 county and State of New York, have invented a certain new and useful Improvement in Mittens, of which the following is a specification.

The invention relates to lined, waterproof mittens or hand coverings, and the object of the invention is to provide a simply constructed, loosely fitting mitten which may be easily drawn on and worn to protect the hand and arm of the wearer from wet and 15 cold, and quickly removed when a more efficient use of the fingers is required. The improved mitten is designed more particularly for use by men in various branches of army service; men serving in the trenches and 20 under like conditions of exposure suffer greatly from cold and wet hands and arms, resulting in a lowering of efficiency due to discomfort and ailments thus induced. Waterproof gloves may be worn to resist 25 the wet but even when equipped with the usual linings do not afford the desired protection against combined wet and cold, and if fitted to the hand, cannot be removed quickly. The present invention permits 30 sufficient use of the hand in digging and analogous exposed operations while fulfilling the necessary requirements of warmth and dryness under all circumstances, and the mitten may be instantly removed when 35 occasion requires.

The invention consists in certain novel features of construction by which the above objects are attained, to be hereinafter described and claimed.

40 The accompanying drawings form a part of this specification and show the invention as it has been carried out in practice.

Figure 1 is a plan view of the palm face of the improved mitten, partly broken away to show a horizontal section along one edge or side.

Fig. 2 is a transverse section taken on the line 2—2 in Fig. 1.

Fig. 3 is a similar view taken on the line 3—3 in the same figure.

Fig. 4 is a plan view of the palm portion before the insertion of the thumb-piece.

Fig. 5 is a face view of the blank forming such thumb-piece.

Fig. 6 is a similar view showing the thumb-piece folded and stitched ready for insertion. 55

Fig. 7 is a perspective view showing the thumb-piece in place.

Similar letters of reference indicate the 60 same parts in all the figures.

The mitten is composed of two distinct, independently formed parts, the outer cover A and the inner lining B. The cover is of waterproof material, preferably double texture rubberized cloth consisting of two layers of cotton fabric with a layer of rubber between them, and the lining is of warmth retaining material, preferably canton flannel for reasons of economy and efficiency. Each is constructed similarly to the other in all particulars, but the lining is smaller, about half an inch smaller in every direction in practice, so as to produce a practically continuous air-space m between the 75 lining and cover in all parts of the mitten when the lining is in position within the cover. 70

As the cover and lining are thus alike, a description of the former will suffice for 80 both. The hand portion and inner gauntlet portion are in a single piece bilaterally symmetrical, and the back is exactly the same in dimensions and contour, so that these parts may be cut in quantities by dies or otherwise 85 without regard to "rights or lefts" or "fronts or backs" except that each front or palm portion is provided with a V-cut N to form the thumb opening and provide an angular tongue A¹ therein. In assembling, 90 care must be taken to have such openings oppositely located for the right and left hand mitten of each pair, as will be understood.

The thumb-piece C is formed bilaterally 95 symmetrical as shown in Fig. 5, folded on the center line c c and stitched as at C¹ part way to the base to produce the desired pocket having an inclined margin C² at the base or open end. This inclined margin matches to 100 the outer sides of the angular cut N in the palm portion and is joined to the latter by stitches A², while the tongue A¹ is raised and stitched between the open margins of the thumb-piece by stitches A³ and forms the 105 equivalent of the usual gusset.

As before stated the lining B is similarly made in all respects but of smaller dimen-

sions, and is simply inserted within the cover A and joined thereto at the rear extremity or opening of the gauntlet by parallel circumferential lines of stitches A⁴ and A⁵; and to 5 prevent the lining from leaving the interior of the cover in the act of withdrawing the hand, the lining and cover are joined by a few stitches A⁶ at the extreme end of the palm portion.

- 10 In the circumferential pocket between the cover and lining formed by the stitches A⁴ A⁵, an elastic band D is inclosed, serving to hold the gauntlet snugly but yieldingly to the arm of the wearer, and on the wrist line 15 of the cover on the inside face of the palm portion is stitched a short length of similar elastic, as at D¹, serving to constrict lightly the palm portion across the wrist of the wearer.
- 20 The gauntlet may be of any length but preferably extends well up on the upper arm nearly to the shoulder.

The front and back pieces of the cover A are joined along their edges by a continuous 25 line of stitches A⁷ except at the mitten opening, and the front and back pieces of the lining are similarly joined by a line of stitches B¹.

The seams of the cover may be felled and 30 treated as usual to insure against the entrance of water along the lines of stitches therein.

By making the cover portion of waterproof fabric all dampness is excluded, and 35 by making the lining of heat-retaining material warmth and comfort is insured, and by providing the considerable air-space in all parts of the mitten between the cover and lining, the latter is well insulated from the 40 former and the warmth of the hand and arm efficiently conserved.

The manufacture is extremely simple and inexpensive.

By the words "completely formed" I mean

that the lining pieces are sewed together to 45 form a complete mitten, and the outside pieces are sewed together to form a complete mitten; then the inner mitten is thrust inside the outer mitten and the two stitched together at the wrist only.

It will be understood that the invention 50 may be applied to gloves or other forms of hand coverings, but for army purposes the simple mitten is considered preferable.

I claim:—

1. In a mitten or the like, an outer cover 55 of waterproof material, having the front and back alike and each bilaterally symmetrical and joined to form a complete mitten-structure, and a lining portion of warmth-retaining material having the front and back alike and each bilaterally symmetrical and joined to form a complete mitten-structure similar to but smaller than said cover, inserted within the latter and joined thereto by stitching 60 together the margins of the mitten-opening of each and the extreme ends of the hand portions of each to provide a continuous air-space between said lining and cover in all 65 parts of such mitten.

2. In a mitten or the like, a palm portion 70 having a V-shaped cut therein producing an angular tongue, and a thumb-piece folded upon itself and having its side margins stitched together from the end partially to 75 the base margins, said base margins stitched to the palm portion along the lines of said cut, and the said tongue stitched to said thumb-piece along the open unstitched portions of said side margins, and a lining 80 formed independently of the palm portion and disposed within the mitten and disconnected therefrom substantially throughout its entire area.

In testimony that I claim the invention 85 above set forth I affix my signature.

HANS J. DIEM.
